COLOMAN DE KANDO, OF BUDAPEST, AUSTRIA-HUNGARY.

ELECTRIC MACHINE.

No. 853,550.

Specification of Letters Patent.

Patented May 14, 1907.

Application filed December 13, 1906. Serial No. 347,572.

To all whom it may concern:

Be it known that I, COLOMAN DE KANDO, a subject of the King of Hungary, and a resident of Felsö erdösor 12, Budapest, in the 5 Empire of Austria-Hungary, have invented certain new and useful Improvements in or Relating to Electric Machines; and I hereby declare the following to be a full, clear, and exact description of the invention, such as 10 will enable others skilled in the art to which it appertains to make and use the same.

My invention relates to electric machines with divided windings arranged in grooves, and more especially to an arrangement to 15 protect the portions of the winding projecting outward at the ends of the machine, on the one hand, against outside influences of any kind, and on the other hand, against heating produced by short overloads. To 20 that end, the surface of the frame is provided with circular covers which completely inclose the winding portions in question, and which have the shape of a casing and into which is cast or introduced a suitable insulating mass, 25 the melting point of which is above the normal heating, in such manner that the portions of the winding projecting at the front ends of the iron frame, are completely and firmly embedded in the solidified mass. In 30 this way the winding portions are completely protected from moisture, excellently insulated and in addition to that, the wires are prevented from rubbing against each other and spoiling the insulation, more particularly in the case of railway motors exposed to 35 vibrations acting on the freely suspended portions of the winding. Owing to its high specific heat capacity, the mass exercises a favorable influence on the coiling, more particularly in the case of strong overloads of 40 the motor, lasting only for a short time. When the overload of the machine heats the winding to the point of melting of the mass, the absorption of the heat during the melting 45 produces an efficient cooling effect. This arrangement was found however to have the serious drawback that when the mass was melted, it passed through the grooves of the iron frame into the air gap between the frame 50 and the armature or rotor and when the mass subsequently cooled, it solidified, and caused the armature or rotor to stick fast.

These drawbacks are obviated according to this invention by the annular casing surrounding the projecting portions of the winding being provided with means allowing free

escape to the mass when melted from the circular casings. For this purpose I provide said circular casings at their lowest point with suitable openings.

Owing to the coils of the winding being uniformly distributed in the whole melting mass, if the winding is heated, the mass is melted in a uniform manner, so that a high hydrostatic pressure is forcing out the molten or softened mass through the openings in question. The escaping and solidifying mass forms a strip, so that the heating of the motor is at once recognized by the appearance of such a strip.

Owing to the provision of a free outlet for the molten mass, in passing through which the mass has to overcome a smaller resistance than when penetrating into the slits between the grooves of the frame and the windings placed therein, the molten mass does not penetrate into the frame or stator and does not cause the armature or rotor to stick.

A construction according to this invention is diagrammatically illustrated in the accompanying drawing which shows a three-phase motor in longitudinal section.

The portions 2 of the winding, projecting at the two end faces of the frame 1, are inclosed in a circular casing constituted by a 85 cover 3 and the sheet metal cylinder 4. Into this casing is cast a solid insulating mass 5 the melting point of which corresponds to the highest admissible temperature. At the lowest point, the casing is provided with a 90 hole 6 through which the molten insulating mass 5 can pass when melted in the shape of a strip or strand, 7.

In order to render the filling up with the molten insulating mass easy, the case 3, 4 95 can be provided at its highest point with an opening 8 over which can be arranged a funnel or supply tank 9. The insulating mass contained in the tank 9 is melted by conduction when the winding is heated, and is 100 drawn in as the molten mass escapes at the bottom.

Having now described my invention what I claim is:—

1. In electric machines, with windings arranged in the grooves of the stator, portions of the winding projecting at the faces of the stator, means forming circular casings including said projecting parts of the windings, a solid insulating mass adapted to melt when the winding is heated above the normal point in said circular casing embedding the

projecting parts of the windings, means to prevent said mass when melted from entering the space between the stator and the rotor.

5. 2. In electric machines, with windings arranged in the grooves of the stator, portions of the winding projecting at the faces of the stator, means forming circular casings including said projecting parts of the windings, a solid insulating mass adapted to melt when the winding is heated above the normal point in said circular casing embedding the projecting parts of the windings, means allowing free escape of the mass when melted from said circular casings.

3. In electric machines, with windings arranged in the grooves of the stator, portions of the windings projecting at the faces of the stator, means forming circular casings including said projecting parts of the windings, a solid insulating mass adapted to melt when the winding is heated above the normal point in said circular casing embedding the projecting parts of the windings, suitable 25 opening in said circular casings allowing free escape of the mass when melted.

4. In electric machines with windings arranged in the grooves of the stator, portions of the winding projecting at the faces of the stator, means forming circular casings including said projecting parts of the windings, a solid insulating mass adapted to melt when the winding is heated above the normal point in said circular casing embedding the projecting parts of the windings, suitable openings at the lowest part of said circular casing allowing free escape of the mass when melted.

5. In electric machines with windings arranged in the grooves of the stator, portions of the winding projecting at the faces of the stator, means forming circular casings including said projecting parts of the windings, a solid insulating mass adapted to melt when the winding is heated above the normal point in said casing embedding the projecting parts of the windings, means to prevent said mass when melted from entering the space between the stator and the rotor and means to allow a supply for the insulating mass into said circular casings.

6. In electric machines, with windings arranged in the grooves of the stator portions of the winding projecting at the faces of the stator, means forming circular casings including said projecting parts of the windings, a solid insulating mass adapted to melt when the winding is heated above the normal point in said circular casing embedding the projecting parts of the windings, means allowing free escape of the mass when melted from said circular casings and means to allow a supply for the insulating mass into said circular casings.

65. 7. In electric machines, with windings ar-

ranged in the grooves of the stator, portions of the winding projecting at the faces of the stator, means forming circular casings including said projecting parts of the windings, a solid insulating mass adapted to melt when the winding is heated above the normal point in said circular casing embedding the projecting parts of the windings, suitable openings in said circular casing allowing free escape of the mass when melted and means to allow a supply for the insulating mass into said circular casings.

8. In electric machines with windings arranged in the grooves of the stator, portions of the winding projecting at the faces of the stator, means forming circular casings including said projecting parts of the windings, a solid insulating mass adapted to melt when the winding is heated above the normal point in said circular casing embedding the projecting parts of the windings, suitable openings at the lowest part of said circular casings allowing free escape of the mass when melted and means to allow a supply for the insulating mass into said circular casings.

9. In electric machines with windings arranged in the grooves of the stator portions of the winding projecting at the faces of the stator, means forming circular casings including said projecting parts of the windings, a solid insulating mass adapted to melt when the winding is heated above the normal point in said circular casing embedding the projecting parts of the windings, means to prevent said mass when melted from entering the space between the stator and the rotor, suitable charging openings in said circular chambers allowing a supply of the insulating mass.

10. In electric machines, with windings arranged in the grooves of the stator portions of the winding projecting at the faces of the stator, means forming circular casings including said projecting parts of the windings, a solid insulating mass adapted to melt when the winding is heated above the normal point in said circular casing embedding the projecting parts of the windings, means allowing free escape of the mass when melted from said circular casings, suitable charging openings in said circular chambers allowing a supply of the insulating mass.

11. In electric machines, with windings arranged in the grooves of the stator portions of the winding projecting at the faces of the stator, means forming circular casings including said projecting parts of the windings, a solid insulating mass adapted to melt when the winding is heated above the normal point in said circular casing embedding the projecting parts of the windings, suitable openings in said circular casings allowing free escape of the mass when melted, suitable charging opening in said circular chambers allowing a supply of the insulating mass.

12. In electric machines with windings ar-

5 ranged in the grooves of the stator, portions of the winding projecting at the faces of the stator, means forming circular casings including said projecting parts of the windings, a solid insulating mass adapted to melt when the winding is heated above the normal point in said circular casing embedding the projecting parts of the windings, suitable openings at the lowest part of said circular casings allowing free escape of the mass when melted, 10 suitable charging openings in said circular chambers allowing a supply of the insulating mass.

13. In electric machines with windings arranged in the grooves of the stator, portions of the winding projecting at the faces of the stator, means forming circular casings including said projecting parts of the windings, a solid insulating mass adapted to melt when the winding is heated above the normal point in said circular casing embedding the projecting parts of the windings, means to prevent said mass when melted from entering the space between the stator and the rotor, suitable charging openings at the highest part of 25 said circular casings.

14. In electric machines, with windings arranged in the grooves of the stator, portions of the winding projecting at the faces of the stator, means forming circular casings including said projecting parts of the windings, a solid insulating mass adapted to melt when the winding is heated above the normal point in said circular casing embedding the projecting parts of the windings, means allowing free escape of the mass when melted from said circular casings, suitable charging openings at the highest part of said circular casings.

15. In electric machines, with windings arranged in the grooves of the stator portions of the winding projecting at the faces of the stator, means forming circular cases including said projecting parts of the windings, a solid insulating mass adapted to melt when the winding is heated above the normal point in said circular casing embedding the projecting parts of the windings, suitable openings in said circular casings allowing free escape of the mass when melted, suitable charging openings at the highest part of said circular casings.

16. In electric machines with windings arranged in the grooves of the stator, portions of the winding projecting at the faces of the stator, means forming circular casings including said projecting parts of the windings, a solid insulating mass adapted to melt when the winding is heated above the normal point in said circular casing embedding the projecting parts of the windings, suitable openings at the lowest part of said circular casings allowing free escape of the mass when melted, suitable charging openings at the highest part of said circular casings.

17. In electric machines with windings arranged in the grooves of the stator, portions of the winding projecting at the faces of the stator, means forming circular casings including said projecting parts of the windings, a solid insulating mass adapted to melt when the winding is heated above the normal point in said circular casing embedding the projecting parts of the windings, means to prevent said mass when melted from entering the space between the stator and the rotor, suitable charging openings in said circular chambers allowing a supply of the insulating mass and supply tanks communicating with said charging openings.

18. In electric machines with windings arranged in the grooves of the stator, portions of the winding projecting at the faces of the stator, means forming circular casings including said projecting parts of the windings, a solid insulating mass adapted to melt when the winding is heated above the normal point in said circular casing embedding the projecting parts of the windings, means allowing free escape of the mass when melted from said circular casings, suitable charging openings in said circular chambers allowing a supply of the insulating mass and supply tanks communicating with said charging openings.

19. In electric machines with windings arranged in the grooves of the stator, portions of the winding projecting at the faces of the stator, means forming circular casings including said projecting parts of the windings, a solid insulating mass adapted to melt when the winding is heated above the normal point in said circular casing embedding the projecting parts of the windings, suitable openings in said circular casing allowing free escape of the mass when melted, suitable charging openings in said circular chambers allowing a supply of the insulating mass, and supply tanks communicating with said charging openings.

20. In electric machines with windings arranged in the grooves of the stator, portions of the winding projecting at the faces of the stator, means forming circular casings including said projecting parts of the windings, a solid insulating mass adapted to melt when the winding is heated above the normal point in said circular casing embedding the projecting parts of the windings, suitable openings at the lowest part of said circular casings allowing free escape of the mass when melted, suitable charging openings in said circular chambers allowing a supply of the insulating mass and supply tanks communicating with said charging openings.

21. In electric machines with windings arranged in the grooves of the stator, portions of the winding projecting at the faces of the stator, means forming circular casings including said projecting parts of the windings, a

solid insulating mass adapted to melt when the winding is heated above the normal point in said circular casings embedding the projecting parts of the windings, means to prevent said mass when melted from entering the space between the stator and the rotor, suitable charging openings at the highest part of said circular casings, and supply tanks communicating with said charging 10 openings.

22. In electric machines, with windings arranged in the grooves of the stator, portions of the winding projecting at the faces of the stator, means forming circular casings including parts of the windings, a solid insulating mass adapted to melt when the winding is heated above the normal point in said circular casing embedding the projecting parts of the windings, means allowing free escape of 15 the mass when melted from said circular casings, suitable charging openings at the highest part of said circular casings and supply tanks communicating with said charging 20 openings.

23. In electric machines, with windings arranged in the grooves of the stator, portions of the winding projecting at the faces of the stator, means forming circular cases including said projecting parts of the windings, a 25 solid insulating mass adapted to melt when

the winding is heated above the normal point in said circular casings embedding the projecting parts of the windings, suitable openings in said circular casings allowing free escape of the mass when melted, suitable charging openings at the highest part of said circular casings and supply tanks communicating with said charging openings. 35

24. In electric machines with windings arranged in the grooves of the stator, portions of the winding projecting at the faces of the stator, means forming circular casings including said projecting parts of the windings, a solid insulating mass adapted to melt when the winding is heated above the normal point 40 in said circular casing embedding the projecting parts of the windings, suitable openings at the lowest part of said circular casings allowing free escape of the mass when melted, suitable charging openings at the highest 45 part of said circular casings and supply tanks communicating with said charging openings. 50

In testimony whereof, I have signed my name to this specification in the presence of two subscribing witnesses.
